(57) CLAIM

The ornamental design for a magnifying glass, as shown and described.

DESCRIPTION

FIG. 1 is a top and side perspective view of a magnifying glass, showing my new design;

FIG. 2 is a top elevational view;

FIG. 3 is a bottom elevational view;

FIG. 4 is a side elevational view thereof;

FIG. 5 is a side elevational view thereof, taken from the side opposite to that shown in FIG. 4;

FIG. 6 is an end elevational view thereof, taken from the right of FIG. 3; and,

FIG. 7 is an end elevational view.
